DEVICE FOR SHAPING EYEBROWS
AND THE LIKEDwight C. Hudson, Chicago, Ill., assignor to The
Wm. Meyer Company, Chicago, Ill., a corpora-
tion of Illinois

Application January 7, 1935, Serial No. 593

15 Claims. (Cl. 128—355)

This invention relates to a device for shaping eyebrows and the like and may be characterized as an improvement upon the device and method illustrated and described in the copending application of William Meyer, filed July 14, 1934, Serial No. 735,097.

The present invention relates to a device and method for arching eyebrows upon living human skin. In order to accomplish this it is necessary to introduce the strands of hair individually between the rolls. Unless this is done, the desired shaping of the eyebrows cannot be obtained. For example, if straight, or even tapered, rolls are applied sidewise or laterally to the hair, all of the strands of hair in a given line will be simultaneously engaged between the rolls with the result that even if these strands could be satisfactorily pulled from the skin, the pulling simultaneously of all strands of hair along the line of coaction of the rolls would preclude entirely any possible shaping of the eyebrow.

The object of my present invention is to provide a simple and inexpensive device for shaping eyebrows with ease and facility and without discomfort.

Another object is to provide a device of this sort comprising a pair of rotatable rolls having pointed ends in rolling contact and adapted to grasp the strands of hair individually and generally endwise with means for separating the pointed end of at least one roll from the pointed end of the other roll to facilitate introduction of the strands of hair therebetween.

Another and more specific object is the provision of means operated by the turning movement of the rolls for separating the pointed ends thereof, and still more specifically, means on one roll and cooperable with the other roll for separating the pointed ends of the rolls during the turning movement thereof.

Another object is the provision of means for yieldingly holding the hair engaging portions of the rolls in rolling contact.

Another object is the provision of an improved mounting for permitting separation of the hair engaging portion of at least one roll from the hair engaging portion of the other roll, and more specifically, an improved mounting permitting pivotal action of one roll to separate the pointed end thereof from the pointed end of the other roll during the turning movement of the rolls.

Another object is the provision, in a device of the character described, of a handle casing, a pair of rolls rotatably journaled in the casing and having pointed ends in rolling contact and

adapted to grasp strands of hair individually and generally endwise, and a guide secured to the casing and having a notched end in close proximity to the pointed ends of the rolls.

Further objects and advantages of the invention will be apparent from the following detailed description, taken in connection with the accompanying drawings, in which:

Figure 1 is a side view of a machine embodying the present invention;

Figure 2 is a side view of the handle casing, showing the coacting pointed ends of the hair pulling rolls;

Figure 3 is a detailed section taken on the line 3—3 of Figure 2;

Figure 4 is an enlarged longitudinal section taken on the line 4—4 of Figure 3;

Figure 5 is a detail section taken on the line 5—5 of Figure 4;

Figure 6 is a fragmentary section, similar to Figure 4, partially in elevation, and showing the means for separating the pointed end of one roll from the pointed end of the other roll in operation;

Figure 7 is a detail section taken on the line 7—7 of Figure 4;

Figure 8 is a fragmentary top plan view of another embodiment of the invention;

Figure 9 is a side view of the embodiment shown in Figure 8;

Figure 10 is a longitudinal section through the embodiment of Figures 8 and 9, and partially in elevation; and

Figure 11 is a perspective view of another form of device embodying one of the features of the present invention.

Referring now more particularly to Figure 1, the reference numeral 1 indicates a standard having a base 2 and an upright 3, at the upper end of which is disposed a head 4. The head 4 carries a swingingly mounted yoke 5 in which an electric motor 6 is supported as by means of a pair of trunnions 7 or the like.

The motor 6 is provided with conduit means 10 controlled by an electric switch 11 of any suitable construction. The motor 6 includes a casing 12 containing gear reduction means of any suitable character, and the casing 12 supports the casing of a flexible connector 13 of well-known construction, such as one in the form of a flexible conduit enclosing a flexible wire or other drive transmitting means.

The flexible connector 13 terminates in a head or sleeve 15 and, in Figures 2 and 3, it will be

noted that the sleeve is provided with a notched slot 17.

In the embodiment of Figures 1 to 7, inclusive, the hair pulling implement comprises a head or handle casing 20 having a generally cylindrical portion 21, and, at its forward end, a laterally enlarged portion 22. The rear end of the cylindrical portion 21 is open and internally threaded to receive an elongated sleeve 23 threaded externally for engagement with the internal threads in the cylindrical portion 21. A shaft 24, constituting one of the rolls, is journaled in the sleeve 23 and has a forward reduced end 25 which passes through an opening 26 in the front of the casing 20. Fixed upon the shaft 24 within the casing 20 and between the forward end of the sleeve 23 and the front end of the casing is a bevel pinion 27.

The laterally enlarged portion 22 has a generally cylindrical interior, the axis of which converges forwardly toward an extension of the axis of the cylindrical portion 21. The rear end of the interior of the laterally enlarged portion 22 is open to receive a cap 28 having a reduced extension 29 telescoping rather tightly in the rear end of the interior of the laterally enlarged portion 22 and secured therein as by means of a screw 30. The inner end of the extension 29 is bifurcated at 31 to receive a flat-sided tongue 32 at the rear end of an extension 33 on a shaft 34, which constitutes the second hair pulling roll. The shaft 34 bears at its rear end in the extension 33 and, at its forward end, passes through an opening 35 in the front of the casing 20. The shaft 34 is journaled within the casing in a bushing 36. This bushing 36 has a spherical forward end 37 seated in a spherical seat 38 in the forward end of the casing 20.

The engagement of the spherical forward end 37 of the bushing 36 in the spherical seat 38 provides, in effect, a ball and socket action for permitting the forward end of the shaft 34 to separate from the forward end of the shaft 24 during the turning movement of the shafts for the purpose of facilitating the introduction of the strands of hair therebetween. The engagement of the tongue 32 in the bifurcated end 31 of the cap 28 prevents swiveling or pivotal movement of the shaft 34 about the ball and socket joint except toward and from the outer end of the shaft 24.

The shafts 24 and 34 terminate at their outer ends in tapered or pointed tips 40 and 41, respectively, the outer ends of which tips may be relatively sharp or rounded slightly. The tapered ends 40 and 41 are normally in rolling contact as shown in Figures 1, 2 and 4. Fixed upon the shaft 34, within the casing 20, and between the forward end of the extension 33 and the bushing 36, is a bevel pinion 42 which meshes with the pinion 27 and turns the shaft 34 by the turning movement of the shaft 24 and in a direction opposite thereto.

The extension 33 has a laterally opening pocket 45, and a coiled spring 46 in this pocket engages the inner end of the pocket and the casing 20 at its opposite ends for yieldingly holding the pointed end 41 of the shaft or roll 34 in rolling contact with the pointed end 40 of the shaft 24 or roll 24.

The angular relation between the shafts 34 and 24 permits the rolling contact of the tapered ends of the shaft, and the pinions 27 and 42 gear the shafts to rotate in opposite directions.

To permit the pointed end of the shaft 34 to

pivot from and toward the pointed end of the shaft 24, the opening 35 is elongated transversely of its axis and in a direction to permit this movement. Since the pinion 27 is securely fixed to the shaft 24 this shaft is, by this means, held against axial displacement in the casing 20. Similarly, the pinion 42 being fixed to the shaft 34, the bushing 36 is held in place thereby, and, with the spring 46, the shaft 34 is held yieldingly in cooperation with the shaft 24.

The shaft 24 forms the driving shaft for the rotatable roll assembly and, to this end, the rear portion of the shaft 24 is hollowed out as at 50, and is slotted as at 51 for the purpose of receiving the end of a driving pin 52 having a feather 53 adapted to enter the slot 51. The driving pin 52 is operatively connected with the flexible driving means enclosed within the conduit 13.

The rearmost end of the sleeve 23 carries a pin 54 which is adapted to be received within the laterally angled portion 55 of the slot 17, this means forming a bayonet joint between the head 15 of the driving conduit and the casing or operating head 20. The conduit sleeve 15 carries a spring-pressed plunger 56, and when the head or casing 20 is applied with the pin 54 entering the slot or notch 17 against the tension of the spring-pressed plunger 56, the pin is adapted to enter the annular notch 55, whereby the head or casing 20 is secured to the conduit casing and, at the same time, the feather 53 enters the slot 51 in the driving shaft 24. Hence the actuation of the electric switch causes the motor 6 to drive the rolls 24 and 34 at considerable speed and in the direction of the arrows shown in Figure 2.

In Figure 2, I have shown the general position of the device when the same is in operation in shaping or arching an eyebrow, indicated by the reference numeral 60. The pointed ends 40, 41 are engageable generally endwise and individually with the strands of hair as indicated, for example, at 61 in Figure 2. The strand to be pulled enters individually between the pointed ends of the rolls, and as soon as the strand of hair is seized by the pointed ends of the rolls rotating in the directions indicated by the arrows in Figure 2, it is withdrawn from the live skin by being pulled upwardly and backwardly therefrom. The backward pull is the result of the strands of hair being fed toward the casing 20 as they enter between the pointed ends of the rolls, and this feeding of the strands toward the casing is the result of the tendency of the hair to travel toward the larger diameter portions of the pointed ends 40 and 41 in much the same manner in which a belt tends to travel toward the larger diameter of a "crown" pulley.

To facilitate entry of the strands of hair between the pointed ends of the rolls, means is provided for separating the pointed end of at least one roll from the pointed end of the other roll during the turning movement of the rolls. This means comprises cam means on the pointed end of one roll for engagement with the other roll to separate the pointed ends in the illustrated embodiment, once during each rotation of the roll 24.

The particular roll separating cam means selected for illustration comprises a pin 65, secured rigidly in a diametrical opening in the pointed end of the roll 24. The outer end of this pin 65 is headed or projects slightly at 66 to contact the roll 34 and separate the same from the roll 24 by the turning movement of the rolls and against the tension of the spring 46 which tends to hold the pointed ends in engagement. The separated

position of the pointed end of the roll 34, as the head or projecting end of the pin 65 engages the same, is indicated in dotted lines in Figure 5.

The casing 20 is used as a hand piece in the 5 operation of the device. The pointed ends of the rolls and the endwise application of the same enables the device to be applied individually to the strands of hair for pulling the same individually to shape the eyebrow as desired. The 10 spring pressure against the roll 34 and the separation of this roll from the roll 24 in the operation of the device provides for accommodation of the strands of hair between the conical or pointed ends of the rolls. As soon as the strand of hair is 15 well between the conical or pointed ends 40 and 41 there is a tendency for the hair to work rearwardly as the rolls rotate and it is engaged and plucked by this upward and backward action of the rolls. The tapered surfaces of the rolls are 20 engaged generally laterally and directly with the adjacent skin, and this lateral engagement holds the skin down and prevents discomfort during the 25 plucking or pulling operation.

In the operation of the device, the motor 6 is 25 energized and the hand piece or casing 20 is held generally in the position shown in Figure 2. Then the device is moved progressively along the 30 eyebrow, as to the left in Figure 2, so that the hairs to be removed are directed between the pointed ends of the rolls. The rapidly rotating 35 rolls withdraw the hairs and the latter are, at the same time, shifted rearwardly to permit the entrance of other hairs, so that the eyebrow may be quickly and conveniently shaped by a uniform movement of the hand piece 21. A suitable plug connector 70 is provided for the motor 6.

In the embodiment of Figures 8, 9 and 10, the 40 casing 20' has the cylindrical portion 21' in which the sleeve 23' is mounted, and the roll 24' is rotatably journaled in this sleeve and provided with the bevel pinion 27'. The rear end of the sleeve 23' is provided with the connecting pin 54', and the forward end of the roll 24' is conical or pointed at 40' and provided with the headed pin 45 66' or other cam means for engaging the pointed end 41' of the roll 34' for separating the pointed ends by the rotation of the rolls and during the 50 operation of the same.

In this embodiment, the rear end of the 55 internal cylindrical portion of the lateral extension 22' is internally threaded to receive the threaded extension 75 of a cap 76.

In this embodiment, the inner end of the extension 75 has a bore 77 provided with a flat bearing washer 78, and the adjacent end of the roll 34' fits relatively loosely in the bore 77 and has point-bearing contact at its rounded end with the washer 78. The bevel pinion 42', fixed on the roll 34', meshes with the bevel pinion 27', as 60 before, and the opening 35' is elongated transversely of the axis of the roll 34' and in a direction to permit swinging of the pointed end 41' about the rear end of the roll toward and from the 65 pointed end 40' of the roll 24'. For the purpose of yieldingly holding the pointed end 41' in rolling contact with the pointed end 40', the lateral extension of the casing 20' has an opening 79 threaded at its outer end to receive a plug 80. A 70 plunger 81 has engagement laterally with the roll 34', and a coiled spring 82, interposed between the plug 80 and the plunger 81, holds the plunger yieldingly against the roll 34' and the 75 pointed end of this roll yieldingly against the pointed end of the other roll.

The embodiment of Figures 8, 9 and 10 is applied and operated in the manner of the embodiment of Figures 1 to 7 inclusive. A guide 84, in the form of a flat thin strip, may be secured to the casing 20' by means of a screw 85. The outer end of this guide is turned, as shown in Figure 8, to lie in close proximity to the pointed ends 40' and 41', and is provided with a notch 86 which registers with the line or space between the pointed ends of the rolls in which the strands of hair are received. In operation, the guide 84 guides the device over the skin, and the notched end 86 engages the skin laterally with the pointed ends of the rolls closely disposed with respect thereto. As a result, the guide holds the skin down during the pulling operation and prevents 15 discomfort.

The device shown in Figure 11 is similar to the device more fully illustrated and described in the copending application of Bruno Wehner, Serial 20 No. 745,171, filed September 24, 1934, except that it is provided adjacent the plucking prongs 90 and 91, with a guide 92 secured to one side of the forward end 93 of the device and provided with 25 a notched end in close proximity to the pointed ends of the plucking prongs in the manner of the embodiment of Figures 8, 9 and 10.

I do not intend to be limited to the precise details shown or described.

I claim:

1. A device for shaping eyebrows, comprising a pair of rolls having pointed ends held in engagement and adapted to grasp the strands of hair individually and generally endwise, means for turning the rolls in opposite directions, and cam means on the pointed end of one roll for separating the pointed end of one roll from the pointed end of the other roll during the turning movement of said rolls.

2. A device for shaping eyebrows, comprising a handle casing and a pair of rotatable rolls journaled therein and having pointed ends arranged to have rolling contact and engageable generally endwise and individually with the strands of hair, the journal for one of said rolls comprising a bushing having a spherical end seated in a spherical seat in said casing to support said roll for separation of its pointed end from the pointed end of the other roll during rotation of said rolls.

3. A device for shaping eyebrows, comprising a handle casing, a pair of rotatable rolls journaled therein and having pointed ends arranged to have rolling contact and engageable generally endwise and individually with the strands of hair, the journal for one of said rolls comprising a bushing having a spherical end seated in a spherical seat in said casing to support said roll for separation of its pointed end from the pointed end of the other roll during rotation of said rolls, and means for preventing pivotal movement of the roll provided with said bushing except toward and from said other roll.

4. A device for shaping eyebrows, comprising a handle casing, a roll rotatably journaled therein, means for turning said roll, a second roll disposed with its axis oblique with respect to the axis of said first roll, said rolls having pointed ends in rolling contact and adapted to grip the strands of hair of the eyebrow individually and generally endwise, a pinion on said first roll, a meshing pinion on said second roll, and a bushing for said second roll swiveled in said casing.

5. A device for shaping eyebrows, comprising a handle casing, a roll rotatably journaled there-

in, means for turning said roll, a second roll disposed with its axis oblique with respect to the axis of said first roll, said rolls having pointed ends in rolling contact and adapted to grip the 5 strands of hair of the eyebrow individually and generally endwise, a pinion on said first roll, a meshing pinion on said second roll, a bushing for said second roll swiveled in said casing, a cap secured to said casing at the end opposite the 10 pointed end of said second roll and having a bifurcated extension, and an extension on said second roll having a tongue engaging in said bifurcated extension for preventing swiveling of the pointed end of said second roll except toward and 15 from the pointed end of said first roll.

6. A device for shaping eyebrows, comprising a handle casing, a roll rotatably journaled therein, means for turning said roll, a second roll disposed with its axis oblique with respect to the axis of 20 said first roll, said rolls having pointed ends in rolling contact and adapted to grip the strands of hair of the eyebrow individually and generally endwise, a pinion on said first roll, a meshing pinion on said second roll, a bushing for said second 25 roll swiveled in said casing, a cap secured to said casing at the end opposite the pointed end of said second roll and having a bifurcated extension, an extension on said second roll having a tongue engaging in said bifurcated extension for 30 preventing swiveling of the pointed end of said second roll except toward and from the pointed end of said first roll, said extension having a laterally opening pocket, and a coiled spring fitted in said pocket and engaging the inner end thereof and the casing at its opposite ends for yieldingly holding the pointed end of said second roll in 35 cooperation with the pointed end of said first roll.

7. A device for shaping eyebrows, comprising a handle casing, a roll rotatably journaled therein, said roll extending through an opening in said casing and having a pointed end externally of the casing, and a second roll extending through an opening in the casing and having a pointed 40 end for rolling contact with the pointed end of said first roll, the opening provided in the casing for one of said rolls being elongated transversely of its axis and in a direction to permit movement of the pointed end of one of said rolls toward and from the pointed end of the other roll.

8. A hair plucking device comprising a pair of rolls having pointed ends held in engagement and adapted to grasp hair individually and generally endwise, means mounting one of said rolls for 45 tilting movement in a plane disposed longitudinally of the axes of said rolls, means for turning said rolls, and means for tilting the roll mounted for tilting movement in its plane of tilting movement as set forth and during the turning movement of said rolls to facilitate the introduction of the hair therebetween.

9. A device for shaping eyebrows comprising a pair of coacting rotatable rolls for plucking the 50 strands of hair of the eyebrow, said rolls having pointed ends in close rolling coaction and engageable generally endwise with the hair for picking up and feeding individually the strands of hair endwise between the rolls, means mounting one of said rolls for tilting movement in a plane disposed longitudinally of the axes of said rolls, means for turning said rolls, and means operable by the turning movement of one of said rolls for tilting the roll mounted for tilting movement 55 in its plane of tilting movement as above 70

set forth, whereby to separate the pointed end of one of said rolls from the pointed end of the other roll for the introduction of the strands of hair therebetween.

10. In combination, a pair of coacting tapered hair plucking rolls having coacting pointed ends engageable generally endwise and individually with the strands of hair, means for turning the rolls in opposite directions, means mounting one of said rolls for tilting movement in a plane disposed longitudinally of the axes of said rolls, and means operable by the tilting movement of one of said rolls for tilting the roll mounted for tilting movement in its plane of tilting movement as above set forth, whereby to separate the 15 pointed end of one of said rolls from the pointed end of the other roll for the introduction of the strands of hair therebetween.

11. A device for shaping eyebrows comprising a pair of rolls having pointed ends held in engagement and adapted to grasp hair individually and generally endwise, means mounting one of said rolls for tilting movement in a plane disposed longitudinally of the axes of said rolls, means for turning said rolls, and means on one 20 of said rolls and operable by the turning movement of said roll for tilting the roll mounted for tilting movement in its plane of tilting movement as above set forth.

12. In combination, a pair of hair plucking 30 rolls having portions in rolling contact and adapted for individually plucking the strands of hair, means for turning the rolls in opposite directions, means mounting one of said rolls for tilting movement in a plane disposed longitudinally of the axes of said rolls, and means for tilting the roll mounted for tilting movement in its plane of tilting movement as set forth and during the turning movement of said rolls to facilitate the introduction of the hair therebetween.

13. In combination, a pair of hair plucking rolls having portions in rolling contact and adapted for individually plucking the strands of hair, means for turning the rolls in opposite directions, means mounting one of said rolls for tilting movement in a plane disposed longitudinally of the axes of said rolls, and means for tilting the roll mounted for tilting movement in its plane of tilting movement as set forth and during the turning movement of said rolls to facilitate the introduction of the hair therebetween, said last means comprising a cam element carried by one of said rolls.

14. In combination, a pair of hair plucking rolls having portions in rolling contact and adapted for individually plucking the strands of hair, means for turning the rolls in opposite directions, means mounting one of said rolls for tilting movement in a plane disposed longitudinally of the axes of said rolls, means for tilting the roll mounted for tilting movement in its plane of tilting movement as set forth and during the turning movement of said rolls to facilitate the introduction of hair therebetween, and spring means yieldingly holding the hair engaging portion of the roll mounted for tilting movement in cooperation with the hair engaging portion of the other roll.

15. In combination, a pair of hair plucking 70 rolls having pointed ends held in engagement and adapted to grasp the strands of hair individually and generally endwise, means for turning one of said rolls, a pinion on said roll, a meshing pinion on the other roll for turning 75

said other roll in the opposite direction, means mounting one of said rolls for tilting movement in a plane disposed longitudinally of the axes of said rolls, and means carried by one of said 5 rolls and operated by the turning movement of said roll for tilting the roll mounted for tilt-

ing movement in the plane of tilting movement as set forth and during the turning movement of said rolls to facilitate the introduction of the hair therebetween.

DWIGHT C. HUDSON. 5
